UNITED STATES PATENT OFFICE.

WILLIAM J. NESBITT, OF LOS ANGELES, CALIFORNIA.

HEEL-CUTTING APPARATUS.

1,218,304.

Specification of Letters Patent.

Patented Mar. 6, 1917.

Application filed October 2, 1916. Serial No. 123,439.

To all whom it may concern:

Be it known that I, WILLIAM J. NESBITT, a citizen of the United States of America, residing at Los Angeles, county of Los Angeles, State of California, have invented a certain new and useful Heel-Cutting Apparatus; and I do hereby declare the following to be a full, clear, and exact description of the invention, such as will enable others skilled in the art to which it appertains to make and use the same.

This invention relates to heel cutting apparatus, and it may be said to consist in the provision of the novel and advantageous features, and in the novel and improved construction, arrangement, and combination of parts and devices as will be apparent from the description and claims which follow hereinafter.

20 The objects of this invention are to provide a novel and improved adjustable heel holder, and to simplify and improve the construction which is disclosed in my Patent No. 1,170,178, dated February 1, 1916.

25 Other objects and the advantages of the invention will be apparent to those skilled in the art from a careful consideration of the following description of the preferred form of the modified construction, taken in 30 connection with the accompanying drawings in which—

Figure 1 is a side elevational view of the modified heel cutting apparatus; Fig. 2 is an enlarged sectional view taken on the line 35 2—2 of Fig. 1; Fig. 3 is an enlarged side elevational view of a portion of the apparatus shown in Fig. 1; Fig. 4 is a plan view of the same; Fig. 5 is a rear end elevational view of the same; Fig. 6 is a sectional view 40 taken on the line 6—6 of Fig. 3; Fig. 7 is an elevational view of the guide and post for the heel holder; Fig. 8 shows enlarged elevational and plan views of the sleeve to which the heel holder jaws are connected; Fig. 9 is 45 a sectional view taken on the line 9—9 of Fig. 3; and Fig. 10 is a plan view of one of the heel holder jaws.

As seen in Figs. 1 and 3 of the drawings, the shelf 11 has its rear part secured to the 50 support 12 by screws 13, and on said shelf 11 is movably mounted the platform 14 which has on its underside the dovetail guide 15 which is slidably fitted in a corresponding guideway in the shelf 11. The 55 support 12 has its upper part provided with an extension 16 on which is mounted the ad-

justable bearing 17 for the shaft 18 on which the pulley 19 is loosely mounted. A band saw 20 passes around the pulley 19 and around the pulley 21 which is arranged fast 50 on the shaft 22 which latter is mounted in the bearing 23 on the support 12. The band saw 20 is guided and held in adjusted position by means of suitable devices indicated at 24 and 25.

On the platform 26 at the rear of the support 12 is mounted the motor 27 which has fast on its shaft 28 the spur pinion 29 which meshes with the spur wheel 30 which is mounted fast on the shaft 22 to drive the 70 latter and consequently the band saw 20.

A guide 31 having thereon the post 32 is adjustably mounted on the platform 14 and fitted in a dovetail guideway 33 in the platform 14; said guideway 33 extending substantially at a right angle to the guideway for the guide 15 on the platform 14. On the post 32 is fitted the sleeve 34 which carries the jaws for holding or clamping the heel 35 of the shoe 36. As shown the lower 30 heel clamping jaw 37 is provided with an annular offset 38 fitted adjustably on the sleeve 34 and adapted to be locked in adjusted position by the set screw 39. The upper heel clamping jaw 40 is provided with an offset stub shaft 41 which is fitted in a bearing 42 on the sleeve 34. To the stub shaft 41 is connected the operating lever 43 provided with the handle 44. The jaws 37 and 40 are preferably provided with projecting parts 45 adapted to fit in the crease between the heel seat and the heel 35 of the shoe 36. The sleeve 34 can be locked in adjusted position by means of the thumbnut 46 on the threaded upper end of the post 32.

The guide 31 can be adjusted by means of the lever 47 which is provided with a slot 48 through which extends a projection 49 on the guide 31; said lever 47 having a handle 50 on its forward end and having its other end connected to a pivot 51 on an extension 52 of the platform 14. The guide 31 can be locked in adjusted position by means of the latch 53 which is mounted on a pivot 54 between ears 55 on the lever 47, and is 95 adapted to fit in notches 56 which are provided on the extension 52. A spring 57 is arranged to normally press the latch 53 into engagement with the notches 56.

Movement of the platform 14 can be 110 effected by any suitable or approved means; that shown consisting of the foot lever 58

which is pivotally connected to the support 12, the rod 59 which is pivotally connected to the foot lever 58 and to the arm 60 which is secured to the pivot 61 bearing in the 5 downward extension 62 on the shelf 11, the arm 63 which is secured to the pivot 61, and the curved link 64 which has one end pivotally connected to the arm 63 and has its other end pivotally connected to the side of 10 the platform 14. If desired the handle 65 may be suitably operatively connected to the arm 63.

The operation and advantages of the construction above described will be apparent 15 to those skilled in the art. The jaw 37 can be adjusted on the sleeve 34 to suit the different sized heels, and the heel 35 can be easily and quickly placed and clamped by the jaws 37 and 40 because the lever 43 is 20 offset and spaced from the jaws 37 and 40 sufficiently to be out of the way and permit a clear view in placing the heel to be clamped by the jaws. When the heel 35 is gripped by the jaws 37 and 40, the lever 47 25 can be operated to move the guide 31 according to the amount that is to be cut off of the heel 35. Then by operating the foot lever 58 or the handle 65 the platform 14 is operated and thereby moved to have the 30 cutter or band saw 20 cut the heel 35. When it is desired to make a straight cut of the heel 35 the lever 43 and consequently the sleeve 34 are moved to have the jaws 37 and 40, which are disposed in substantially the 35 same vertical plane, disposed parallel to the band saw 20 before the cut is made. When it is desired to make an angular cut of the heel 35 the lever 43 and consequently the sleeve 34 are turned until the jaws 37 and 40 are turned to have the jaws make the desired angle to the cutter or band saw 20. After adjusting the jaws 37 and 40 according to the cut to be made in the heel 35, the sleeve 34 is locked in position on the post 32 45 by the locknut 46.

The construction which has been particularly illustrated and described admits of changes and modifications, wherefore the right is reserved to all such changes and 50 modifications as do not depart from the spirit and scope of the invention which is defined in the appended claims.

I claim:

1. In heel cutting apparatus, the combination of a movably mounted platform, a 55

guide adjustably mounted on the platform, a post on said guide, a sleeve fitted on said post, and heel clamping jaws carried by said sleeve.

2. In heel cutting apparatus, the combination of a movably mounted platform, an adjustable guide mounted on the platform, a post on said guide, a sleeve fitted on said post and provided with a bearing, a heel clamping jaw having an offset portion connected to said sleeve, a lever provided with a stub shaft mounted in said bearing, and a heel clamping jaw connected to said stub shaft.

3. In heel cutting apparatus, the combination of a movably mounted platform, a guide adjustably mounted on the platform, a post on said guide, a sleeve fitted on said post, a heel clamping jaw adjustably connected to said sleeve, and a heel clamping 75 jaw pivotally connected to said sleeve.

4. In heel cutting apparatus, the combination of a movably mounted platform, a post movably mounted on the platform, a sleeve pivotally mounted on said post, and heel clamping jaws mounted on said sleeve.

5. In heel cutting apparatus, the combination of a movably mounted platform, a post mounted on the platform and adjustable transversely to said platform, a sleeve 85 pivotally mounted on said post and provided with a bearing, a heel clamping jaw provided with an offset portion adjustably connected to said sleeve, a lever provided with a stub-shaft fitted in said bearing, and a heel clamping jaw connected to said stub shaft.

6. In heel cutting apparatus, the combination of a movably mounted platform, a guide mounted on and movable transversely 95 to said platform, a post on said guide, a sleeve pivotally mounted on said post and provided with a bearing, a clamping jaw provided with an offset portion adjustably connected to said sleeve, a lever provided with a stub shaft fitted in said bearing, a heel clamping jaw connected to said stub shaft, and means on said post for locking the sleeve in adjusted position.

In testimony whereof, I have signed my 105 name to this specification at Los Angeles, county of Los Angeles, State of California, this 25th day of September, A. D. 1916.

WILLIAM J. NESBITT.
